R. C. BLACK.
FOLDING ARTICLE HANGER.
APPLICATION FILED OCT. 23, 1914.

Patented Sept. 12, 1916.

UNITED STATES PATENT OFFICE.

ROBERT C. BLACK, OF DUNNELLON, FLORIDA.

FOLDING ARTICLE-HANGER.

1,197,898.

Specification of Letters Patent. Patented Sept. 12, 1916.

Application filed October 23, 1914. Serial No. 868,321.

To all whom it may concern:

Be it known that I, ROBERT C. BLACK, a citizen of the United States, residing at Dunnellon, in the county of Marion and State of Florida, have invented certain new and useful Improvements in Folding Article-Hangers, of which the following is a specification.

My invention relates to folding article hangers.

The primary object of my invention contemplates the provision of a folding article hanger which necessitates for its operation and occupation but a limited amount of space and may be folded up at the will of the user.

Another object of my invention contemplates the provision of a folding article hanger which is constructed of very few parts and is simple and durable in nature and efficient in operation and wherein various structural details of the entirety complement each of the other structural details in performing one or more functions thereof.

With the foregoing and other objects in view this invention consists in such novel features of construction, combination and arrangement of parts as will be hereinafter more fully described, illustrated in the accompanying drawings and claimed.

In describing my invention in detail reference will be had to the accompanying drawings wherein like characters of reference designate like or corresponding parts and in which:—

Figure 1 is a side elevation of my invention showing the same as disposed in position adapted for immediate use. Fig. 2 is an end elevation of my invention showing the same in position as illustrated in Fig. 1. Fig. 3 is a sectional side view of my invention on the line 3—3 of Fig. 2 showing the relation and position of the respective parts when the entirety is folded up. Fig. 4 is a detail view of the prop used in my invention.

In order to clearly illustrate the application of my invention I have shown a support or base 1 to which are attached in spaced alined relation a pair of brackets 2 and 3. The upper of said brackets generally designated by 2 has a body portion 4 which is attached to the base 1 and has outstanding therefrom and at right angles thereto an arm 5 which has a bearing opening formed therein. The lowermost of said

brackets designated by 3 also has a body portion 4 and has an outstanding arm at right angles thereto. However, the length of the said arm on said bracket 3 is shown as being slightly longer than the arm of the bracket 2 in order to impart the proper position to my hanger.

The structural details of my hanger include a prop 6 which has two projections 7 and 8 formed on the upper and lower extremities respectively. Adjacent the projections 7 are a pair of outstanding extensions 9 having bearing openings formed therein. The preferred material used in the construction of my invention consists of semi-cylindrical bars of sheet iron, thus should the manufacturer desire, the projections may be formed by cutting away a portion of the sides and rounding out the remaining material to make it slightly thicker than the rest. Pivotal secured by means of pins 10 to the extension 9 is the arm 11 the opposite end of which is bifurcated to form extensions 12 provided with bearing openings for the reception of pins 13 carried by rib 14. The rib 14 extends upwardly past the arm 11 and is provided with an article hanger 15. To complete the bracing means for the arm 11 I provide a second rib 16 which is pivotally secured by means of the pin 17 to the rib 14. The opposite end of the rib 16 is journaled by means of the pin 19 within the body of the prop 6.

In order to allow for sufficient pivotal movement of the folding parts it is necessary to cut away and bifurcate the upper end of the rib 16 to form extension 18 through which is journaled the pin 17 before referred to, this particular structure allows for inward movement of the said ribs when desiring to fold my hanger; outward movement being eliminated because of the abutment of the terminal end of the body portion of the rib 16 with the upper surface of the rib 14.

When folding my invention in the smallest possible space the ribs 14 and 16 are forced inwardly and the arm 11 is thereby caused to move downwardly into close proximity with the prop 6 when in this position the rib 14 is contained within the semi-cylindrical structure of the arm 11 and the rib 16 is contained within the semi-cylindrical structure of the prop 6, thus forming a very compact package.

Each and all of the parts of my invention

must by necessity be contained within some one of the other parts with the exception of the prop 6 to accomplish this the size of the parts are varied—the rib 14 being the 5 narrowest, the rib 16 slightly larger and the arm 11 of less size than the prop 6 but larger than either of the ribs so that they may be contained within the structure of the prop and arm.

10 I desire it to be understood that I may make slight change in the combination and arrangement of parts without departing from the spirit of my invention provided such changes fall within the scope of the 15 subjoined claims.

Having fully described my invention what I claim as new and desire to secure by Letters Patent is:—

I claim:

20 1. A folding article hanger, including a pair of spaced apart brackets, a prop revolvably mounted between and within said brackets, an arm pivoted to said prop and a pair of pivotally connected ribs forming a

brace engaged by said arm and pivotally 25 connected to said prop, said brace adapted to be folded up and contained within said arm and prop at predetermined times, and means disposed on said brace for supporting an article of apparel. 30

2. In an article hanger, the combination with supporting brackets, of a prop revolvably mounted between said brackets, an arm pivoted to said prop, said prop and arm being of a semi-cylindrical configuration and 25 substantially U-shaped in cross section, and foldable means engaging said prop and arm for bracing the latter when in extended position, said means adapted to be incased within said prop and arm, when in folded 40 position.

In testimony whereof I affix my signature in presence of two witnesses.

ROBERT C. BLACK.

Witnesses:

W. J. METCALF,
C. O. SAIRCLOTH.
